APPARATUS FOR LIMING WIRE

Charles D. Johnson, Worcester, Mass., assignor to
 Johnson Steel & Wire Company, Inc.,
 Worcester, Mass., a corporation of Massachusetts

Application July 16, 1931, Serial No. 551,071

4 Claims. (Cl. 91—46)

In carrying out wire-drawing operations it is the common practice to dip the bundles of wire to be drawn in a bath of lime water before the drawing operation. It is also the common practice 5 to keep the lime bath agitated so as to prevent the lime from settling to the bottom by introducing steam into the bottom of the bath through a perforated steam pipe. The steam thus introduced bubbles up through the bath keeping it 10 more or less violently agitated. The use of steam for this purpose, however, gradually dilutes the lime bath because of the continual condensation of steam therein so that at the end of any given period of time, such for instance as a day's run, 15 the lime bath will be considerably thinner than at the beginning of said period. As a result it is necessary to add lime to the bath from time to time in order to maintain it at substantially 20 constant strength.

One of the objects of the present invention is 25 to provide a novel apparatus for liming wire which is so constructed that the necessary agitation of the lime water may be carried out without in any way diluting or thinning the lime 30 solution. With my improvements, therefore, the lime bath will have a constant strength from one 35 end of the day's run to the other so that all the bundles of wire treated during the day's run or any other period of time will be subjected to 40 the same liming operation.

In prior apparatus steam is used for 45 keeping the bath agitated the introduction of steam into the bath not only dilutes it as above stated but also heats the bath and maintains it 50 hot. Where the hot lime bath is used the heat of the bath is apt to melt off some of the so-called "sulcoat" or "rustcoat" with which the wire is 55 commonly provided prior to the liming operation and as a result the sulcoat or rustcoat which is left on the wire will be more or less unevenly 60 distributed over the surface thereof.

In the liming apparatus herein disclosed the 65 agitation of the lime is secured without heating the bath and the bath may be, therefore, kept 70 at a cool temperature. This is an advantage 75 because the dipping of the sulcoated or rust- 80 coated wire into a cool lime bath tends to harden 85 and set the sulcoat rather than to melt it off and 90 the application of the lime coating to the wire 95 is effected without distributing in any way the 100 previously applied sulcoat.

Another object of the invention is to provide a 105 novel construction which is provided with means for continuously straining or screening the lime 110 bath thereby removing therefrom any sand, grit

or other foreign matter which is likely to injure the dies through which the wire is drawn or to cause imperfections in the wire during the drawing 115 operation.

One way of securing the above-mentioned objects of the invention is by providing means for withdrawing the lime water from the bottom of the lime vat and introducing it again to the top of the vat thus keeping up a constant circulation 120 of lime water through the vat or tank.

In the drawing wherein I have illustrated a 125 selected embodiment of my invention, Fig. 1 is a perspective view of a liming apparatus embodying the invention;

Fig. 2 is a section on the line 2—2, Fig. 1; 130

Fig. 3 is a section on the line 3—3, Fig. 1.

In the drawing 1 indicates a lime vat adapted 135 to contain lime water and 2 indicates bundles of wire which are shown as immersed in the lime 140 water for the purpose of being limed. These 145 bundles are shown as carried by a suitable carrier indicated generally at 3 and which comprises a cross bar 4 adapted to rest on the top 150 of the vat 1 and a wire-supporting bar 5 suspended from the cross bar 4. One end of this 155 wire-supporting bar 5 is pivoted at 6 to an arm 160 7 depending from the cross bar 4 and the other 165 end of the wire-supporting bar 5 is adapted to be 170 detachably secured to the end of another suspender arm 8 depending from the other end of 175 the bar 4.

As shown the suspender arm 8 is bifurcated at 180 its end to receive the end 9 of the bar 5 and said 185 bar 5 is locked to the suspender 8 by means of a pin 10 inserted through the suspender 8 and end 190 9 of the wire-supporting bar 5. The cross bar 4 195 is provided with an eye bolt 11 to which a chain, 200 cable or other lifting element 12 may be attached 205 for lifting the wire carrier 3 and the wire from the 210 tank and transporting the wire to any desired 215 location. This form of wire carrier is 220 representative of a construction which is more or less 225 commonly used in wire-liming operations.

In accordance with my present invention I 230 provide means for withdrawing the lime water 235 from the bottom of the vat 1 and delivering it 240 back into the vat through the top thereof thereby 245 keeping the lime water thoroughly agitated. As 250 herein shown the vat 1 is provided with a sloping 255 or conical bottom 13 and connected to this bottom 260 is a pipe connection 14 which leads to the 265 inlet of a suitable pump 15. The discharge of 270 the pump communicates with a discharge pipe 275 16 which is constructed to deliver into the vat 1. 280 When the pump is in operation the lime water 285

is withdrawn from the bottom of the tank 1 and returned to the top thereof thereby keeping it thoroughly agitated.

- Means are preferably provided for straining the lime water as it is delivered back to the tank again. For this purpose the tank is provided near its top with a side extension 17 forming a sort of hopper which communicates with the interior of the vat 1 through an opening in the side wall of the vat. This opening is adapted to be closed by a screen 18 which forms a partition between the hopper 17 and the vat 1. The end 19 of the delivery pipe 16 is arranged to deliver into the hopper 17 and the lime water which is thus withdrawn from the bottom of the tank 1 is delivered back into the hopper 17 and then flows back into the tank through the strainer 18, the function of which is to strain the lime water and to remove any sand, grit or other foreign matter which may be contained in the lime water. The presence of such sand or grit not only is apt to injure the dies but is also harmful to the wire being drawn in that it is likely to produce imperfections therein. By thus continually screening the lime bath the latter will be kept free from these harmful ingredients with the result that the dies will last longer and a better quality of wire can be produced.

The screen 18 is preferably removable so that it can be taken out to be cleaned or repaired. As herein shown the screen is provided with a frame 20 which is mounted in suitable guiding ways 21 formed at the sides of the opening between the hopper 17 and the tank 1. This screen can be removed by simply lifting it out of the guiding ways 1 and can be easily replaced. With this construction the lime water in the tank 1 is kept circulating through the tank and is thus kept constantly agitated and this agitation, which prevents the lime from settling, is accomplished without changing in any way the character of the lime water, as is done where the agitation is accomplished by means of steam. Furthermore, with this apparatus there is no heating of the lime water during the agitation so that the lime bath may be kept at a cool temperature which is found to give advantageous results in that the application of the lime coat to the wire may be secured without melting or disturbing the previously applied sulcoat.

Another advantage of maintaining the lime bath at a cool temperature is that the cold lime sticks to the wire better than hot lime and lubricant.

cating value of the lime coating is thereby increased.

I claim:

1. An apparatus for liming wire comprising a tank to contain lime water, which tank is open at its top to permit bundles of wire to be dipped therewith and to be removed therefrom, a hopper secured to one wall of the tank on the exterior thereof, a removable screen forming the dividing wall or partition between the hopper and the tank, whereby liquid delivered to the hopper flows through the screen into the tank, and a pump device to withdraw lime water from the bottom of the tank and deliver it to the hopper. 80 85

2. An apparatus for liming wire comprising a lime tank to contain lime water, said tank being open at its top to permit bundles of wire to be dipped therewith and removed therefrom, a hopper secured to the side wall of the tank on the exterior thereof, a screen forming the partition or dividing wall between the hopper and the tank, and means to withdraw lime water from the bottom of the tank and deliver it to the hopper, said lime water flowing from the hopper through the screen into the tank. 90 95 100

3. An apparatus for liming wire comprising a lime tank to contain lime water, said tank being open at the top to permit bundles of wire to be dipped therewith and removed therefrom, a hopper integral with the tank on one side thereof and situated exterior thereof, the wall of the tank having an opening where the hopper is located to provide communication between the hopper and tank, a removable screen normally closing said opening, and a pump device to withdraw lime water from the bottom of the tank and deliver it to the hopper, said lime water flowing from the hopper into the tank through the screen. 105 110 115

4. An apparatus for liming wire comprising a tank to contain lime water, said tank having a conical bottom and being open at the top to permit bundles of wire to be dipped therewith and removed therefrom, a hopper secured to the side wall of the tank on the exterior thereof, a screen forming the partition or dividing wall between the hopper and the tank, and a pump element having its inlet connected to the bottom of the tank and its discharge delivering into the hopper and operating to withdraw lime water from the tank and deliver it to the hopper, the lime water flowing from the hopper into the tank through said screen. 120 125 130
